FOLDING EXTENSION DEVICE

Harry M. Gann, Montclair, N. J., assignor to
 Jacques Kreisler Manufacturing Corporation,
 North Bergen, N. J., a corporation

Application February 3, 1948, Serial No. 6,040

6 Claims. (Cl. 24—71)

1

This invention relates to clasps for wrist watch bands and the like, and more especially to clasps of the folding extension type.

It is the primary aim and object of the present invention to provide a clasp of this type of which the foldable parts are locked in closed relation by positive latch action, rather than by the well-known expediency of interwedging them which entails rapid wear and early breakdown of the lock.

It is another important object of the present invention to provide a clasp of this type with a manually releasable latch which functions reliably and has little bulk, yet is of sturdy and lasting construction, and fairly conceals its true identity when performing its designated function.

It is another important object of the present invention to provide the instant clasp with twin extensions each of which is separately foldable and unfoldable, and to construct the latch so that either extension may in its folded condition be snapped into interlocking engagement with the latch without releasing the other extension from interlocking engagement therewith, or either one or both extensions may be released from interlocking engagement with the latch on different manipulation of the latter.

The above and other objects, features and advantages of the present invention will be more fully understood from the following description considered in connection with the accompanying illustrative drawings.

In the drawings:

Fig. 1 is an enlarged perspective view of a clasp embodying the present invention;

Fig. 2 is another enlarged perspective view of the same clasp, showing the same in folded or closed condition in contrast to the unfolded clasp shown in Fig. 1;

Fig. 3 is a section taken on the line 3—3 of Fig. 2;

Fig. 4 perspective illustrates the disassembled parts of latch mechanism used in the present clasp;

Fig. 5 perspective illustrates the disassembled parts of the present clasp;

Fig. 6 is an end view of one of the parts of the clasp as viewed in the direction of the arrow 6 in Fig. 5;

Fig. 7 is an end-elevational view of a detail of the latch mechanism used in the present clasp;

Fig. 8 is a section taken on the line 8—8 of Fig. 7;

Figs. 9 to 11, inclusive, are diagrammatic views illustrating different operating conditions of the latch mechanism; and

Figs. 12 to 14, inclusive, are diagrammatic views illustrating different operating conditions of a modified latch mechanism.

Referring to the drawings, the reference nu-

2

meral 10 designates a clasp which folds and unfolds in the fashion shown in Figs. 1 and 2. Thus, if the instant clasp 10 is, in a manner hereinafter described, interposed in a wrist watch band, for instance, the latter will be snug around the wearer's wrist when the clasp is folded or closed as shown in Fig. 2, and the watch band will be sufficiently extended to be slidable over the wearer's wrist when the clasp is unfolded as shown in Fig. 1.

The clasp 10 comprises a base plate 12, two folding extensions 14 and 16, and a latch mechanism 18 for locking both extensions 14 and 16 in their folded or closed condition. The base plate 12, which may be curved longitudinally as shown in Figs. 1 and 5 to approximate the curvature of the wearer's wrist, is preferably made of precious or non-precious metal in sheet form, and has its opposite side margins rolled into longitudinally extending beads 20 to lend added strength and rigidity to the plate.

Each folding section 14 and 16 consists of a link member 22 and a cover member 24. More particularly, the link member 22 of each extension 14 and 16 is interposed between one end of the base plate 12 and the corresponding cover member 24. The link members 22 may, like the base plate 12 and the cover members 24, be made of any suitable material, preferably precious or non-precious metal in sheet form. The opposite side margins of each link member 22 are, for added strength and rigidity, curled or rolled into longitudinally extending beads 26 (see also Fig. 3), and the opposite ends thereof are deformed in the fashion best shown in Fig. 5 in order to provide hinge parts 28 and 30, respectively. The opposite ends of the base plate 12 are similarly deformed and also notched in the fashion best shown in Fig. 5, in order to provide hinge parts 32, respectively, which are adapted to cooperate with the hinge parts 28 of the link members 22, respectively, in forming, in conjunction with inserted pins 34, hinge connections between the base plate 12 and the link members 22. The link members 22 are preferably longitudinally curved in the fashion shown in Fig. 5, so as to follow the longitudinal curvature of the base plate 12 when they are folded against the latter in the closed condition of the clasp.

The cover members 24 of the folding extensions 14 and 16 may, like the link members 22, be identical and in the form of U-shaped channels having one end closed by a wall 40. Each cover member 24 may be struck from precious or non-precious sheet metal and formed into the shape best shown in Figs. 1, 3 and 5. Each cover member 24 is pivotally connected with its respective link member 22 by a pin 46 (Fig. 5) which extends through aligned holes 44 in the opposite side flanges 42 of the cover member and

3 through the interposed hinge part 36 of the link member 22. The opposite ends of the pin 46 may conveniently be riveted over as at 48' (Fig. 1) so as to prevent removal of the pin from the cover member. The opposite side flanges 42 of each cover member 24 are, in the present instance, provided with additional aligned holes 44 for selective reception of a pin or the like by means of which the adjacent end of a wrist watch band, for instance, (not shown) may removably be secured to the cover member.

As best shown in Figs. 1, 5 and 6, the end wall 40 of each cover member 24 is formed so as to provide opposite slots 50 and inclined cam edges 52 which lead to the entrances to the slots 50, respectively. The slots 50 and cam edges 52 in the endwall 40 of each cover member 24 combine to define a T-type slot of which the slots 50 form aligned branches and the remainder forms a depending branch. The link members 22 are of smaller width than the gaps 54 between the opposite slots 50 in the cover members 24, so that each link member 22 and associated cover member 24 may be unfolded beyond the extent shown in Fig. 1, i. e., into position in which they may extend substantially co-planar with the base plate 12. The slots 50 and cam edges 52 of each cover member 24 are adapted to cooperate with latches 60 in a housing 62. The housing 62, which is conveniently struck from sheet metal and formed into the shape shown in Figs. 4, 7 and 8, is provided with laterally extending bottom flanges 64 which rest on the base plate 12. The latch housing 62 is firmly mounted on the base plate 12 by having portions 66 of the longitudinal beads 20 of the base plate overlap the adjacent ends of the bottom flanges 64 of the latch housing in the fashion shown in Fig. 1, the opposite ends of the latch housing 62 further extending into adjacent notches 70 in the longitudinal beads 20 of the base plate 12 whereby the latch housing 62 is further located on the base plate 12. The latch members 60 may be identical, and each comprises a handle portion 72 and laterally extending fingers 74 and 76. It follows from Fig. 4 that the latch fingers 76 are wider than the latch fingers 74 for a purpose hereinafter described. The latch members 60 are mounted in the latch housing 62 for sliding movement toward each other by having their fingers 74 and 76 received in opposite longitudinal slots 78 in the latch housing 62. The handle portions 72 of the latch members 60 normally extend to the outside of the housing 62 through openings 80 in the end walls 82, respectively. The latch members 60 are normally urged apart by an interposed compression spring 84 (Fig. 4) the opposite end of which surround forward projections 86 on the latch members 60, respectively, so as to remain in operative alignment with the latter. Spring 84 is preferably formed of square convolutions for better anchorage on the projections 86 of the latch members 60.

The slots 50 in the end walls 40 of the cover members 24 are, in the example shown in Figs. 1, 5, 6 and 9 to 11, made of equal depth, while the identical latch members 60 are arranged in the housing 62 in inverted relation to each other, so that a narrow latch finger 74 and a wide latch finger 76 project from each side of the housing 62. Inverted arrangement of the latch members 60, as explained, serves as an expediency to enable the wearer to release either one or both cover members 24 from interlocking relation with the latch members 60 on different manipulation of the latter, and primarily to permit snapping of either

4 cover member 24 into interlocking relation with the latch members 60 without releasing the other cover member if it is in interlocked relation with the latch members 60.

For a better understanding of this feature, reference is had to Figs. 9 to 11, inclusive, in which slots 50 in the cover members 24 and the latch members 60 are diagrammatically illustrated in different coordinated positions. Thus, Fig. 9 shows the fingers 74 and 76 of both latch members 60 in interlocked relation with the slots 50 in both cover members 24, conforming to the condition in which the extensions 14 and 16 are locked in folded or closed position (Fig. 2). Should it be desired to release cover 24' (Fig. 10) from interlocking relation with the latch members 60 without releasing the opposite cover member 24'', the latch members 60 may be depressed to the extent indicated in Fig. 10 in which the fingers 74 and 76 that cooperate with the cover member 24' clear the slots 50' in the latter and permit its opening. However, while the latch members 60 are thus depressed for the release of the cover member 24', the wide finger 76 of the latch member 60' is still within the confines of the slot 50' in the opposite cover member 24'', wherefore the latter is retained in interlocked relation with the latch member 60' despite the release of the cover member 24' from both latch members. On the other hand, if it is desired to release cover 24'' from interlocking relation with the latch member 60 without releasing the cover member 24', the latch members 60 are depressed to the extent indicated in Fig. 11, in which latch member 60' releases both covers 24' and 24'', while the opposite latch member 60'' releases cover member 24'', but remains in interlocked relation with cover member 24'.

Should one of the cover members, say member 24'', be presently in interlocked engagement with the latch members 60, and the other cover member 24' is snapped into interlocking relation therewith, the latch members will, prior to their entry into the notches 50' in cover member 24', be forced by the cam edges 52 of the latter into the depressed relative position shown in Fig. 10 in which latch member 60' remains in interlocked relation with the cover member 24'' and thus prevents release of the latter. Likewise, if the cover member 24' is presently in interlocked relation with the latch members 60, and the opposite cover member 24'' is snapped into interlocking relation with the latch members, the latter will momentarily be depressed into the relative position shown in Fig. 11, in which cover member 24' is still in interlocked relation with latch member 60'', as will be readily understood.

Thus, either or both cover members 24 may be released from interlocking relation with the latch members 60, depending on the extent to which each latch member is depressed, as will be readily understood. Likewise, either cover member 24 may presently be in interlocked relation with the latch members 60, and the other cover member may be snapped into interlocking relation therewith, without releasing the cover member that is already locked.

Figs. 12 to 14, inclusive, diagrammatically illustrate a modified arrangement of the latch members 60 and the slots 50 in the cover members 24. Thus, instead of providing the latch members with fingers of different width, as in the case of the previously described latch members 60, the instant latch members 60a have fingers 90 which are of equal width. However,

the slots 50a in the cover members 24 are made of different depth. Thus, each cover member 24 has slots 50a' and 50a'' which are of lesser and greater depth, respectively, and the slot 50a' in each cover is confronted by a slot 50a'' in the opposite cover member 24. When both cover members 24 are interlocked with the latch members 60a, the latter assume the relative disposition shown in Fig. 12, in which their fingers 60 are received in all slots of both cover members. If it is decided to release the cover member 24' from the latch members 60a without releasing the opposite cover member 24'', the latch members are depressed to the extent illustrated in Fig. 13, in which cover member 24' is clearly released from the latch members 60a, while cover member 24'' is still in interlocked relation with one of the latch members. Conversely, if it is decided to release cover member 24'' from the latch members 60a without releasing cover member 24', the latch members are depressed to the extent indicated in Fig. 14, in which cover member 24'' is released from the latch members 60a, while the opposite cover member 24' is still in interlocked relation with one of the latch members. Supposing now that cover member 24'' is presently in interlocked relation with the latch members 60a and that the other cover member 24' is snapped into interlocked relation with the same latch members, the cam edges 52 of cover member 24' will then depress the latch members substantially to the extent indicated in Fig. 13 in order to bring the latter into alignment with the slots 50a in cover member 24''. However, during such depression of the latch members 60a, the opposite cover member 24' is at no time released from the latch members, as follows clearly from Fig. 13. Conversely, if cover member 24' is presently interlocked with the latch members 60a and the opposite cover member 24'' is snapped into interlocking relation with the same latch members, the cam edges 52 of the cover member 24'' will momentarily depress the latch members to the extent indicated in Fig. 14, but it will be noted from this figure that cover member 24' is at no time released from the latch members 60a.

While I have shown and described the preferred embodiments of my invention, it will be understood that various changes may be made in the present invention without departing from the underlying idea or principles of the invention within the scope of the appended claims.

Having thus described my invention, what I claim and desire to secure by Letters Patent, is:

1. A folding extension device, comprising a base member, two pairs of cover and link members of which the members of each pair are pivotally connected at their adjacent ends and the ends of said link members remote from said cover members are hingedly connected to the opposite ends of said base member so that said pairs of members are foldable into superposed relation on said base member in two adjacent groups, a latch mounted on said base member for movement transversely thereof between said groups of folded members, said latch having opposite fingers extending longitudinally of said base member, and catches to cooperate with said latch fingers, each catch comprising on said adjacent end of a cover member a depending end wall with a slot adapted for interlock with the adjacent latch finger.

2. A folding extension device, comprising a member, two pairs of cover and link mem-

bers of which the members of each pair are pivotally connected at their adjacent ends and the ends of said link members remote from said cover members are hingedly connected to the opposite ends of said base member so that said pairs of members are foldable into superposed relation on said base member in two adjacent groups, a latch mounted on said base member for movement transversely thereof between said groups of folded members, said latch having opposite fingers extending longitudinally of said base member, and catches to cooperate with said latch fingers, said catches comprising on said adjacent ends of said cover members depending end walls provided with T-type slots, each slot having a first branch adapted for interlock with the adjacent latch finger, and a wedge-shaped branch leading to said first branch and camming the adjacent latch finger into alignment with said first branch on folding the members of the respective pair into said superposed relation on said base member, and said latch being normally yieldingly urged into a position in which its fingers are in interlocking relation with the respective first slot branches.

3. A folding extension device, comprising a base member, two pairs of cover and link members of which the members of each pair are pivotally connected at their adjacent ends and the ends of said link members remote from said cover members are hingedly connected to the opposite ends of said base member so that said pairs of members are foldable into superposed relation on said base members in two adjacent groups, a latch mounted on said base member for movement transversely thereof between said groups of folded members and having opposite fingers extending longitudinally of said base member, and catches to cooperate with said latch fingers, said catches comprising on said adjacent ends of said cover members slotted lugs into and from interlocking engagement with which said latch fingers are movable when the members of said pairs are in said superposed relation on said base member, the slots in said lugs being of equal depth and aligned longitudinally of said base member, and said fingers being of different width depthwise of said slots, so that said latch fingers and associated slotted lugs interlock successively in a certain order, and unlock successively in the opposite order, on movement of said latch to and from interlocking relation with said slotted lugs.

4. A folding extension device, comprising a base member, two pairs of cover and link members of which the members of each pair are pivotally connected at their adjacent ends and the ends of said link members remote from said cover members are hingedly connected to the opposite ends of said base member so that said pairs are foldable into superposed relation on said base member in two adjacent groups, a latch mounted on said base member for movement transversely thereof between said groups of folded members and having opposite fingers extending longitudinally of said base member, and catches to cooperate with said latch fingers, said catches comprising on said adjacent ends of said cover members slotted lugs into and from interlocking engagement with which said latch fingers are movable when the members of said pairs are in said superposed relation on said base member, the slots in said lugs being of different depth with their bottoms aligned longitudinally of said base member, and said fingers being

aligned longitudinally of said base member and of equal width depthwise of said slots so that said latch fingers and associated slotted lugs interlock successively in a certain order, and unlock successively in the opposite order, on movement of said latch to and from interlocking relation with said slotted lugs.

5. A folding extension device, comprising a base member, two pairs of cover and link members of which the members of each pair are pivotally connected at their adjacent ends and the ends of said link members remote from said cover members are hingedly connected to the opposite ends of said base member so that said pairs of members are foldable into superposed relation on said base member in two adjacent groups, opposite latches mounted on said base member for movement transversely thereof between said groups of folded members, each latch having opposite fingers extending longitudinally of said base member, and catches to cooperate with the adjacent fingers of said latches, each catch comprising on the opposite sides and on said adjacent end of a cover member slotted lugs into and from interlocking engagement with which the adjacent fingers of said latches are movable when the members of said pairs are in superposed relation on said base member, the slots in all lugs being of equal depth and the slots in the lugs on the same sides of the folded cover members being aligned longitudinally of said base member, said latches being identical and arranged in inverted relation to one another and the fingers of each latch being of different width depthwise of the slots in the adjacent lugs, so that one latch locks said cover members successively in a certain order and the other latch locks the same cover members successively in the reverse order, on moving said latches into interlocking relation with said catches.

6. A folding extension device, comprising a base member, two pairs of cover and link members of which the members of each pair are pivotally connected at their adjacent ends and the ends of said link members remote from said

5 cover members are hingedly connected to the opposite ends of said base member so that said pairs of members are foldable into superposed relation on said base member in two adjacent groups, opposite latches mounted on said base member for movement transversely thereof between said groups of folded members, each latch having opposite fingers extending longitudinally of said base member, and catches to cooperate with the adjacent fingers of said latches, each catch comprising on the opposite sides and on said adjacent end of a cover member slotted lugs into and from interlocking engagement with which the adjacent fingers of said latches are movable when the members of said pairs are in superposed relation on said base member, the slots in the lugs on the same sides of the folded cover members being of different depth and the slots in the diagonally opposite lugs of the folded cover members being of equal depth, the bottoms of the slots in the lugs on the same sides of the folded cover members being aligned longitudinally of said base member, and said latches being identical and their fingers being aligned longitudinally of said base member and of equal width depthwise of the slots in the adjacent lugs, so that one latch locks said cover members successively in a certain order and the other latch locks the same cover members successively in the reverse order, on moving said latches into interlocking relation with said catches.
